UNITED STATES PATENT OFFICE.

FRANCIS LEE STUART, OF NEW YORK, N. Y.

APPARATUS FOR GATHERING AND CONVEYING MATERIAL.

1,346,390.

Specification of Letters Patent. Patented July 13, 1920.

Application filed August 18, 1919. Serial No. 318,391.

To all whom it may concern:

Be it known that I, FRANCIS LEE STUART, a citizen of the United States, residing at New York city, county and State of New 5 York, have invented certain new and useful Improvements in Apparatus for Gathering and Conveying Material, of which the following is a specification.

This invention relates to apparatus for 10 gathering material and for conveying it to the desired point of delivery. Letters Patent of the United States have heretofore been granted to me for apparatus of this general kind.

15 My U. S. Patent No. 1,271,627 of July 9, 1918 (Case 17) shows apparatus in which the material is gathered by a plow and delivered to a conveyer belt on a boom, which is pivotally connected, to move about both 20 vertical and horizontal axes, with a truck movable over a main conveyer belt which carries the material to its destination.

25 My present invention relates particularly to the construction of the plow used in apparatus of this kind, and also involves devices for agitating the pile of material while being gathered.

30 According to this invention the plow is so constructed as to minimize resistance to the movement of the material onto the conveyer belt of the boom to which the plow delivers, and the boom is provided with rods or arms which serve as agitators for the pile of material in order to preserve a slope 35 in the pile which affords the most easy gathering of material by the plow.

My improvements are illustrated in the accompanying drawings, in which:—

Figure 1 is an elevation of the lower end 40 of a boom conveyer equipped with my improved plow and agitating devices.

Fig. 2 is a plan view of the parts shown in Fig. 1.

Fig. 3 shows a section on the line 3—3 45 of Fig. 2.

Fig. 4 shows a section on the line 4—4 of Fig. 2.

Fig. 5 is a plan, diagrammatical view 50 illustrating the manner in which the apparatus gathers material.

The boom is constructed in any suitable way and it is pivotally connected with a truck T (Fig. 5) mounted to move over a main conveyer belt U arranged between the 55 rails of the track V.

Fig. 1 shows only the lower end of the

boom frame which is lettered A, and in this instance the boom is made in skeleton form, suitably braced or trussed as indicated. The lower end of the boom conveyer belt is indicated at B, and C indicates a frame or housing for the auxiliary conveyer belt D, similar to a belt of this kind shown in my prior patent. The skirt boards of the housing are indicated at c. The belt D is driven 60 by a motor E, geared as shown at e to said belt D. The housing C is continued as shown to the outer edge of the plow F and this extension of the housing contains the rollers or sprockets f for supporting and 65 guiding the lower or outer part of the auxiliary belt. The outer portion of the boom is supported by a tractor G and said tractor may be used for swinging the boom conveyer and gathering devices about the pivotal connection of the boom with the truck. 70 All of these parts are shown in my prior patent or other patents granted to me and are not herein claimed as new.

The plow F is of novel construction. The 75 bottom plate m is preferably made straight and flat and the front and rear edge is inclined from its outer end inwardly and these inclined edges carry teeth m', which facilitate the entrance of the plow into the pile and the gathering of material.

The front and rear sides, as well as the inner side of the plow, are left open. It will be observed that the plow is double acting, that is, it is adapted to gather material when 90 swung in either direction. The top plates N, O of the plow are inclined in a novel way. The plate N inclines from its inner portion downwardly toward the teeth m' and it also inclines inwardly and downwardly toward the boom. The plate O is similarly inclined. Each top plate N and O is adapted to receive material from the teeth m' and to guide it to the conveyer belt D, in the housing C. It will be observed by reference to Figs. 3 and 4 that by this arrangement the distance from the bottom plate m to the top plates N and O is much shorter at the inner part of the plow than at the outer part thereof. This is an improvement of 105 considerable importance, because the inner portion of the plow acts upon material at the edge of the pile as indicated in Fig. 1 where the material is thinner or of less height, and therefore this material may be 110 gathered and transferred to the auxiliary conveyer belt D quickly and with little re-

sistance. The outer portion of plow acts upon the material where the pile is thicker and, furthermore, by having the plates N and O at a higher elevation at the outer portion of the plow, space is provided for the roller or sprocket wheels f.

Experience has demonstrated that a plow constructed in the manner before described operates more efficiently than those heretofore used for a similar purpose.

It will be observed by reference to Fig. 2 that the skirt boards of the casing C terminate at the inner edge of the plow and from these lower ends of the skirt boards project plates J which serve to guide or direct the gathered material onto the conveyer belt. These plates are preferably curved in arcs having radii struck from the vertical axis about which the boom conveyer turns.

I have found that material can be gathered with greater facility if the slope of the pile is maintained at a proper angle. In Fig. 1, X indicates the natural slope of the pile on which the plow is operating and Y indicates the slope after the plow has operated. It sometimes happens, however, that the pile does not maintain the slope indicated at X or Y but the material assumes the conditions shown at Z, and when in this condition the material is not so easily gathered. I have found that this difficulty may be overcome by providing agitators which stir or agitate the material in such manner as to cause it to assume or maintain the proper slope. For this purpose I employ outwardly extending rods P, P', the lower rods P' being shorter than the upper ones. These rods may be rigidly attached to the outer end of the boom, but preferably they are made adjustable as shown. As indicated in Fig. 2, the rods P are pivotally mounted at p and each of these rods is connected by a rod Q to adjusting devices q. It will be observed that the inner end of each rod Q is threaded and a sleeve nut is provided at q which may be operated to draw the rod inward or force it outward and thus adjust the agitating rod to which it is connected. Any suitable device for this purpose may be employed. Fig. 2 clearly indicates a construction which is suitable and it also indicates how the agitating rods may be adjusted in various ways. The lower rods P' may be adjusted in a similar way.

In the operation of the plow indicated in Figs. 1 and 5 when the resistance of the head of the pile is sufficient the material is pushed up the incline by the plow and falls onto the conveyer belt. It will be observed that the sliding surface N O in Fig. 3 is much less than the sliding surface in Fig. 4. There is much greater depth of material over the outer portion of the plow shown in section in Fig. 4, as the material slides up the incline so that with less depth of ma-

terial at the outer edge of the pile or the inner edge of the plow, there is less height and distance for the material to move to reach the conveyer in the central portion of the plow. In this way there is less resistance 70 from the material in front of the plow. With regard to the agitating means shown, these are believed to be of importance, but the agitating means may be varied. I have merely shown the preferred way of performing this operation.

I claim as my invention:

1. Apparatus for gathering and conveying material, comprising a conveyer for the material and a plow delivering thereto provided with a top plate over which the material passes to the conveyer, inclined from its outer edge inwardly and downwardly by the side of the conveyer belt and also from its front edge upwardly and inwardly toward 85 the side of the conveyer belt.

2. Apparatus for gathering and conveying material, comprising a conveyer for the gathered material and a plow delivering to said conveyer, provided with a top plate 90 over which the material passes to the conveyer, which is doubly inclined, viz., from its front receiving edge upwardly toward the conveyer belt and from its outer edge downwardly and inwardly sidewise of the 95 conveyer belt.

3. A plow for reclaiming conveyers, of trapezoidal form, having toothed receiving edges and top plates over which the material passes from the toothed edges which are 100 doubly inclined, viz., from the toothed edges upwardly to their delivery ends and from their outer edges downwardly and inwardly.

4. Apparatus for gathering and conveying material, comprising a boom conveyer 105 mounted to swing about a vertical axis, a gathering plow on the outer end of the boom conveyer, a rod carried by the boom, swinging therewith and extending therefrom across the plow for agitating or stirring the 110 pile of material during the operation of the plow to obtain the desired slope in the pile.

5. Apparatus for gathering and conveying material, comprising a boom conveyer mounted to swing about a vertical axis, a 115 gathering plow on the outer end of the boom conveyer, and rods arranged one above the other carried by the boom, swinging therewith and extending therefrom across the plow for agitating or stirring the pile of 120 material during the operation of the plow to obtain the desired slope in the pile.

6. Apparatus for gathering and conveying material, comprising a boom conveyer mounted to swing about a vertical axis, a 125 gathering plow on the outer end of the boom conveyer, an agitating rod carried by the boom, swinging therewith and extending therefrom across the plow for agitating or stirring the pile of material during the op- 130

eration of the plow to obtain the desired slope in the pile, and means for adjusting the rod in a horizontal plane to cause it to assume different angles with relation to the 5 plow.

7. Apparatus for gathering and conveying material, comprising a boom conveyer mounted to swing about a vertical axis, a gathering plow on the outer end of the 10 boom conveyer, agitating rods carried by the boom conveyer, swinging therewith and extending therefrom across the plow for agitating or stirring the pile of material during the operation of the plow, and devices 15 for adjusting the rods in a horizontal plane to cause them to assume different angles relatively to each other.

8. Apparatus for gathering and conveying material, comprising a boom conveyer 20 mounted to swing in a horizontal plane, a plow for gathering material on the outer end of the boom conveyer having an inclined front edge arranged diagonally with reference to the longitudinal axis of the 25 boom conveyer, and a plate at the inner end of the edge of the plow which projects forwardly therefrom in the direction in which

the boom conveyer swings and which is curved correspondingly with the arc in which the plow moves.

9. Apparatus for gathering and conveying material, comprising a conveyer, a plow delivering to said conveyer provided with a top plate over which the material passes to the conveyer which is doubly inclined, viz., 35 from its front receiving edge upwardly toward the conveyer belt and from its outer edge downwardly and inwardly sidewise of the conveyer belt, and a curved plate projecting from the inner edge of the plow to 40 direct the material thereto.

10. Apparatus for gathering and conveying material, comprising a conveyer belt, a plow delivering to said conveyer having a toothed front edge and provided with a top 45 plate over which the material passes to the conveyer which is doubly inclined, viz., from its outer edge downwardly toward the inner edge of the plow and from its front or receiving edge upwardly.

In testimony whereof, I have hereunto subscribed my name.

FRANCIS LEE STUART.
